CLAIM

The ornamental design for a hand scrubber, as shown and described.

DESCRIPTION

FIG. 1 is a top plan view of the hand scrubber of the present invention;

FIG. 2 is a bottom plan view of the hand scrubber of FIG. 1;

FIG. 3 is a front elevational view of the hand scrubber of FIG. 1;

FIG. 4 is a rear elevational view of the hand scrubber of FIG. 1; and,

FIG. 5 is a left side elevational view of the hand scrubber of FIG. 1 the right side elevational view being a mirror image thereof.

The broken lines are for illustrative purposes only and form no part of the claimed design.
